UNITED STATES PATENT OFFICE.

EVERETT REYNOLDS, OF WAYNESBURG, KENTUCKY, ASSIGNOR OF ONE-HALF TO
ARAD K. CALDWELL, OF WAYNESBURG, KENTUCKY.

GASOLENE-BURNER.

1,254,277.

Specification of Letters Patent. Patented Jan. 22, 1918.

Application filed April 27, 1917. Serial No. 164,922.

To all whom it may concern:

Be it known that I, EVERETT REYNOLDS, a citizen of the United States, residing at Waynesburg, in the county of Lincoln and 5 State of Kentucky, have invented certain new and useful Improvements in Gasolene-Burners; and I do hereby declare the following to be a full, clear, and exact description of the invention, such as will enable others 10 skilled in the art to which it appertains to make and use the same.

This invention relates to improvements in gasolene burners.

The object of the invention is to provide 15 a portable lamp or illuminating device, especially adapted for burning mixed fuel.

Another object of this invention is to provide a lamp capable of burning gasolene, kerosene and alcohol or the like, which is 20 gasified and burned in connection with an incandescent mantle.

A further object of this invention is to provide a lamp of this character, which may be easily kept clean and one that will operate with the highest and best efficiency, 25 and one that will be inexpensive in construction.

A still further object of this invention is to provide a device of this character, which 30 will be simple, practical and comparatively inexpensive in construction, and one that can be manufactured and sold at a low cost.

With these and other objects in view, the invention consists in the novel combination 35 and arrangement of parts as will be herein-after more fully described and set forth in the claim hereto appended.

In the drawings:

Figure 1 is a front elevation of my im- 40 proved burner as made in accordance with this invention,

Fig. 2 is a view taken at right angles to Fig. 1 and partly broken away,

Fig. 3 is a view similar to Fig. 1 partly in 45 section and on an enlarged scale.

Like numerals of reference designate corresponding parts in all the figures of the drawings.

Referring to the drawings, the numeral 1 50 designates a supply pipe, which has arranged thereon at right angles thereto, the controlling valve 2, which has the usual controlling stem and head 3, this being of the needle type. The upper end of the supply pipe is

screwthreaded as at 4 to removably receive a 55 starting cup 5 or priming cup, which has arranged therein, a suitable asbestos or absorbent material 6, which may be saturated with alcohol or the like fuel.

A generator pipe 7 is removably fitted in 60 the supporting cup 5 and communicates with the supply pipe 1 as shown in Fig. 3. The upper end of the generator pipe is screwthreaded as at 8 and is adapted to detachably receive the nozzle 9, which is provided with 65 the central aperture 10, which establishes a communication between the supply and generator pipes and mixing chamber. The mixing chamber 11 above referred to has secured thereto and depending from the under side, 70 the burner pipes 12, which have secured on their lower ends, the mantles 13, and these burner pipes are located adjacent each end of the mixing chamber.

A supporting pipe 14 is secured to the 75 under side of the mixing chamber and depends therefrom and this pipe is located between the burner pipes 12 and has secured thereto, a horizontal coupling 15, which has screwthreaded in each end, the air inlet 80 pipes 16, which are arranged in horizontal alinement, and the coupling 15 is screwthreadedly mounted on the nozzle 9 to establish a communication between the supply pipe and mixing chamber and to permit the 85 fuel to pass into the mixing chamber and be thoroughly mixed with the air where it is then distributed down through the burner pipes and mantles, where it is ignited.

A supporting rod 17 is secured to the upper side of the mixing chamber centrally thereof as at 20 or formed integrally therewith and has its upper end screwthreaded as at 21. A conical hood 22 has its apex fully open and has its peripheral enlarged end 95 bent laterally to provide an annular flange 23, which is substantially horizontal in cross section and this flange is provided with suitable apertures 24, which are adapted to removably support a globe thereto should it 100 be desired.

A substantially U-shaped strap 25 has its circular web portion 26, and the arms of said strap 25 are bent inwardly and directed outwardly in a divergent plane and are secured to the exterior of the conical hood 22 as at 27 at diametrically opposite points. 105

The web 26 is substantially semi-circular

in cross section and is provided centrally with an opening through which extends the threaded end 21 of the rod 17.

A cup-shaped deflector 27' is provided 5 with a central opening and formed on its medial portion on the exterior thereof is a boss 28, which has a screwthreaded opening to receive the upper end of the rod 17 therein and this boss has formed therefrom, a 10 suspending hook 29, which removably supports the device in position. The screwthreaded end 21 is removably fitted in the boss 28 and it securely connects the mixing chamber and its connections with the hood 15 and deflector, thus it can be seen that the heated air radiating from the mixing chamber 11 may readily pass out through the space between the conical shape hood 22 and deflecting member 27, and the deflecting 20 member 27' will deflect rain or other water should the device be hung outside.

In operation, the suitable fuel is placed 25 in the mixing cup or priming cup 5, it is ignited, the valve 3 is opened, the fuel passing up through the pipe 1 into the pipe 7 is heated and vaporized and it will then pass into the mixing chamber, and air is drawn through the intake pipe 16, the air and vaporized gas is thoroughly mixed and 30 distributed through the burner pipes 12 to the mantle 13, where it is ignited. The mixing chamber is arranged in the hood 22, the rod is extended upwardly through the opening in the semi-circular bight portion 35 of the supporting strap 25, the cup-shaped

deflector is screwthreadedly fitted on the threaded end of the rod, thus connecting the structure together and providing a unitary compact arranged device, which may be readily suspended from any suitable support 40 by the hook 29 as illustrated.

What is claimed is:

A burner comprising a supply pipe, a valve in said supply pipe, a generating pipe connected to and communicating with the supply pipe, a starting cup carried by the generating and supply pipe, inlet air pipes connected to and communicating with the generating pipe, a nozzle on the generating pipe and establishing a communication between the inlet and generating pipes, a mixing chamber secured to the inlet pipes, burner tubes depending from the mixing chamber, a rod formed integrally with the upper side of the mixing chamber, a conical shaped hood arranged over the mixing chamber and rod, a substantially U-shaped strap secured to the apex of the hood, and a cup-shaped deflecting member detachably secured to the upper end of the rod to secure 55 the conical shaped hood to the mixing chamber, and means carried by the deflecting cup-shaped member for supporting the device in position.

In testimony whereof I affix my signature 60 in presence of two witnesses.

EVERETT REYNOLDS.
